HARVEY H. HALLER, OF LOS ANGELES, CALIFORNIA, ASSIGNOR TO THE WEHR MOTOR COMPANY, OF LOS ANGELES, CALIFORNIA, A CORPORATION OF CALIFORNIA

VALVE CONSTRUCTION

Application filed July 19, 1930. Serial No. 469,178.

My invention relates to valve constructions, and more particularly those associated with internal combustion engines in which a compensation means is provided for changes in 5 temperature and wear.

It accordingly is an object of my invention to provide a novel form of temperature and wear compensating means for the rotary valves of internal combustion engines comprising

10 a pair of coacting shoes, one being double concave in construction, while the other is plano-convex, the plane surface of which is adapted to conform to the taper of the inner surface of the valve casing or its 15 cover or closure, so there will not only be a wedging action toward and away from said rotary valve, due to an adjustable spring assembly associated with one of said shoes, but also a relative arcuate movement between 20 said shoes, to the end that all temperature and wear changes are at all times effectively compensated for so that there shall be no leakage between said valve and its seat associated with the cylinder ports of said engine. 25 The above and further objects and advantages of my invention, as will hereinafter more fully appear, I attain by the construction described in the specification, and illustrated in its preferred form on the drawing, 30 forming a part of my application.

Reference is had to the accompanying drawing, in which similar reference characters denote similar parts. In the drawing,

Fig. 1 is a transverse cross-sectional view 35 through an internal combustion engine equipped with my invention,

Fig. 2 is a longitudinal sectional view of Fig. 1, on a reduced scale, taken through the vertical center line of said Fig., and

40 Fig. 3 is an enlarged fragmentary detail sectional view through the valve casing illustrating more particularly the cut-out portions thereof.

Describing my invention more in detail, 45 in its broader aspects said invention comprises a rotary valve having associated therewith a pair of preferably spring actuated compensating devices which may take the form of a double concave shoe adapted to be seated 50 on and in engagement with the rotary valve

of an internal combustion engine, with which is associated another shoe, plano-convex in form, having an upper surface adapted to contact with a complementary tapered inner surface of the valve casing or its cover, so that 55 there will not only be a wedging action toward and away from said valve, but there will be a relative arcuate movement between said shoes to the end that all temperature and wear changes in said construction will be 60 effectively compensated for, to avoid all leakage between the valve and its seat.

More specifically, I provide an internal combustion engine 2 with the usual cooling jackets 4 and cylinders 6 having cylinder 65 ports 8, a valve casing or casting 10 being associated with the cylinders 6 in any way in practice preferred.

The valve casing 10 has associated therewith the usual inlet port 12 and exhaust port 70 14, controlled by the rotary valve 16, having cut-out or cut away portions 18 which are adapted selectively to connect the inlet port 12 with the cylinder port 8, and the exhaust port 14 with said cylinder port 8, said valve 75 being adapted to be rotated in the direction of the arrow, any preferred form of spark plug 20 being used in connection with the cylinder 6.

Associated with the valve 16 in any preferred way, but preferably positioned on the top thereof as shown, is a lower compensating valve shoe 21, double concave in construction, which shoe is continually urged toward the valve by the adjustable bolt and spring assembly 22.

Associated with the lower shoe 21, and adapted to move therewith and also relative thereto, is an upper compensating shoe 24, said shoe being plano-convex in construction, 90 the convex portion being adapted to be seated in the upper concave portion of the lower shoe 21, while the upper plane surface of the shoe 24 is adapted to correspond with the taper of the inner surface of the valve casing 95 or its cover or closure 26, which cover or closure may be detachably associated with the valve casing 10 in any preferred way, as by the screw bolts 28.

It will be observed that by reason of the 100

construction just described, an adjustable wedging action is had between the compensating devices 24 and 21 and the valve 16, and moreover, that there will be an arcuate movement of the upper shoe 24, relative to the lower shoe 21, thus at all times holding the valve 16 to its seat, irrespective of all variations of temperature or wear changes, thus insuring that leakage is effectively prevented about said seat.

If desired, the valve 16 may be provided with a set of packing rings 28, in case the engine is of the multi-cylinder type, to obviate any leakage between the cylinder ports 8.

It will also be noted that the valve casing 10 has a cut-out portion 30, connected to a channel or passage 32, which in turn is connected to a piping 34, which piping may lead to a suction means of any character so that the cut-out portion may be subjected to vacuum conditions.

The periphery of the cut-out portion 30, which, it will be noted, embraces a substantial portion of the periphery of the valve 16, is to provide a means for lubricating said valve, the lubricant being introduced in any preferred way, as by the pipe 36, connected with a passage 38 in the valve cover 26, which passage is in alignment with a passage 40 in the upper shoe 24, and the passage 42 in the lower shoe 21.

Suction being maintained in the pipe 34, the lubricant enters the pipe 36, and by reason of the passages 40 and 42, as well as the movement of the shoes 24 and 21 and the rotation of the valve 16, the upper and lower surfaces of each shoe as well as the periphery of the valve 16, by reason of the cut-out portion 30, is at all times effectively lubricated, said passages and cut-out portion being subjected to vacuum conditions by reason of the suction maintained at the pipe 34, the packing rings 28 preventing any leakage between the cylinder ports 8.

If desired, the upper shoe 24 may be provided with a set of slots 44, shown in dotted lines, whereby any inaccuracies due to faulty machining may be compensated for.

In accordance with the provisions of the patent statutes, I have described the principle of operation of my invention together with the apparatus which I now consider to represent the best embodiment thereof; but I desire to have it understood that the apparatus shown is only illustrative, and that the invention can be carried out by other means.

I claim as my invention:

1. In a rotary valve, a compensating device comprising a movable spring-pressed shoe, having concaved upper and lower portions, said lower portion being adapted to engage the periphery of said valve, and a plano-convex backing member having a curved lower portion adapted to engage the upper concaved portion of said shoe, where-

by said valve will be held in continual engagement with its seat, irrespective of temperature and wear conditions in said valve and its seat.

2. A compensating device adapted for special use in connection with rotary valves comprising a shoe having curved upper and lower portions, and a backing member having a plane upper portion and a convex lower portion complementary to the concaved upper portion of said shoe. 70

3. In a rotary valve, a casing therefor, a compensating device comprising an oscillatable shoe and a backing member having an upper plane surface, said backing member being adapted to have a sliding movement with respect to said casing and a relatively oscillating movement with respect to said shoe. 80

4. In a rotary valve, a compensating device comprising a movable spring-pressed shoe adapted to engage said valve, and a movable arcuate backing member having its arcuate portion associated with said shoe and responding in its movements to the movement of said shoe. 85

5. In an internal combustion engine, a valve casing having a tapered inner surface, a rotary valve in said casing, a spring-pressed shoe having its lower surface in engagement with said valve, and its upper surface concaved, and a backing member having its upper surface plane to correspond to the taper of said valve casing, and its lower surface curved to correspond to the curvature 100 of the upper surface of said shoe. 95

6. In a rotary valve, a casing therefor, and a plurality of compensating shoes associated with said valve, one of said shoes being double concave in contour while the other is 105 plano-convex.

7. In a rotary valve, a casing therefor, and a set of spring-pressed compensating shoes associated with said valve, one of said shoes having an upper plane face and a lower convex surface, and another of said shoes having upper and lower concave surfaces. 110

In testimony whereof I have signed my name to this specification.

HARVEY H. HALLER.
